UNITED STATES PATENT OFFICE.

ADAM H. PRENZEL, OF HALIFAX, PENNSYLVANIA, ASSIGNOR TO UNITED SHOE MACHINERY COMPANY, OF PATERSON, NEW JERSEY, A CORPORATION OF NEW JERSEY.

LASTING-MACHINE.

1,117,440.

Specification of Letters Patent. Patented Nov. 17, 1914.

Application filed December 11, 1912. Serial No. 738 079.

To all whom it may concern:

Be it known that I, ADAM H. PRENZEL, citizen of the United States, residing at Halifax, in the county of Dauphin and State of Pennsylvania, have invented certain new and useful Improvements in Lasting-Machines, of which the following is a specification, reference being had therein to the accompanying drawing.

10 This invention relates to machines which are especially adapted for use in connection with the lasting of boots and shoes and is herein shown and described in an embodiment designed particularly for use in lasting 15 stitching-down shoes.

In my co-pending application, Ser. No. 725,477, filed Oct. 12, 1912, for Letters Patent for improvement in machines for use in lasting boots and shoes is shown a machine 20 for progressively lasting stitch-down shoes and securing the upper permanently in lasted position as the lasting progresses, and a general object of the invention is an improvement in a machine of the type disclosed in said co-pending application which will adapt the machine to perform to better advantage certain kinds of work. In the machine of said co-pending application the fastening guiding nozzle is so shaped that 25 it guides the fastening, which is preferably a staple, into the angle between the sole and the last in such position that it holds one side of the upper angle tightly in lasted position upon the side of the last and the other side of the upper angle tightly against the upper face of the sole or of the sole margin. With some kinds of work difficulty has been experienced in forcing the fastening guiding nozzle into the angle in the upper or into the angle between the last and the sole margin without scratching or marring the upper. It will be apparent that 30 the sharpness of the tip of the fastening guiding nozzle or its approximation to an edge is limited by the necessity for having a wall of sufficient strength upon each side of the fastening guiding opening in said nozzle and by the further necessity of having the edge somewhat rounded to prevent cutting 35 of the upper, and that therefore when the angle into which the upper is to be forced is acute, as for example when the upper is to be forced between the insole and outsole margins of a shoe having an insole or into

the angle under an overhanging shoulder 55 upon either an insole or an outsole, the upper will close against the sides of said nozzle before it has reached the vertex of the angle, thus bringing it into such position that it may be cut or rubbed in this process. 60

A particular object of the invention, therefore, is to facilitate the lasting of work in which the upper is to be forced into a comparatively narrow crease or groove.

Another object of the invention is to provide means arranged to operate upon the upper in advance of the fastening guiding means in such manner that the upper is forced substantially into the location in which it is to be secured by the fastening 70 and is so held that the fastening guide can be brought into position to insert a fastening in the location most effective for permanently securing the upper in lasted position. 75

Another object of the invention is to provide means for extending the upper stretching or pulling operation beyond the part of the upper immediately to be secured so that the upper will be drawn smoothly over the last and that preliminary lasting of a portion of the upper subsequently to be permanently lasted will be effected. 80

As above suggested, the invention is embodied in a machine in which the fastening employed is a staple, since a staple is the 85 most convenient and effective of known metallic fastenings for the purposes for which this machine is provided and a further object of the present invention is the provision of improved means associated 90 with the stapling or fastening mechanism whereby the upper will be properly stretched over the last and positioned for stapling so that when the same is stapled, a smooth, neat joint will be formed between 95 the upper and the outer sole.

A further object of the present invention is the provision in a machine of this character of an improved work support and means for adjusting the same enabling the machine 100 to be used with equal efficiency upon shoes of various sizes and shoes having outer soles of different thicknesses.

Other objects of the invention will be apparent from the detailed description herein- 105 after, when read in connection with the accompanying drawings forming a part hereof, wherein a convenient embodiment of the

invention is illustrated, and wherein like characters of reference refer to similar parts in the several views.

In the drawings: Figure 1 is a fragmentary front elevation of the improved machine, parts being omitted for the sake of clearness; Fig. 2 is a fragmentary side elevation of the machine, the anvil or work support being shown in its normal position;

10 Fig. 3 is an enlarged fragmentary side elevation showing, in section, the position occupied by a shoe on the anvil or work support when the anvil has been shifted to position the outer sole of the shoe against the 15 stapling nose of the machine so as to permit a staple to be driven thereinto through said stapling nose.

Referring now more particularly to the drawings, the frame of the machine comprises a pedestal or support A, from the 20 upper end of which extends upwardly a curved arm A', which arm is adapted to support staple forming and setting mechanism. The pedestal or support A of the machine is adapted to be secured upon the floor or any other supporting member. This 25 construction is well known to the art and hence I have deemed it unnecessary to illustrate the same.

30 Supported by any suitable fixed part of the portion of the frame of the machine at the outer end of the curved arm A' is a downwardly directed stapling nose B which is provided with a suitable opening b 35 extending therethrough into which a staple, which has been previously formed, is adapted to be introduced, said staple being driven through the stapling nose B and into the work, which is adapted to be held there- 40 against, by a suitable plunger B' which is adapted to move within the opening of the stapling nose. Suitable staple forming and setting machines, in which staples are formed from a reel of wire carried by the 45 machine, and fed to a stapling nose from which they are driven into the work by a suitably actuated plunger are well known in this art, and as these features form no part of the present invention I have deemed 50 it unnecessary to illustrate the same in the drawings. It will be understood, however, that in the use of the present invention, the operator will, after the work has been 55 pressed against the inside of the stapling nose, by the operation of a suitable lever or other operating member, caused a staple to be driven from the stapling nose thereinto. The lower end of the stapling nose B is 60 conveniently reduced in thickness so that the same will readily enter the space between the edges of the inner and outer soles of the shoe which is to be stapled, in the manner to be hereinafter more particularly set forth.

65 Positioned one on each side of the stapling nose B are a pair of yieldably supported

lasting fingers C C, the lower ends of which normally project below the lower end of the stapling nose B so that as the work is moved upwardly to bring the same into engagement with the stapling nose, the lasting 70 fingers C C will first be engaged by the work and will be moved upwardly therewith until the work is brought into engagement with the lower end of said stapling nose. The lower ends of the lasting fingers C C are 75 conveniently tapered so that such lasting fingers will readily enter the space between the inner and outer sole of the shoe as the same is moved upwardly into engagement therewith, and the front faces of said lasting 80 fingers are curved outwardly as at c c to form wiping surfaces which will engage the upper and draw the same smoothly over the last, and into proper position for stapling as the shoe is moved upwardly into engagement with the stapling nose. In the particular embodiment of the invention illustrated in the drawings, the lasting fingers C C are shown as depending from the branches of a horizontally disposed fork-shaped member C', the stem of which is pivotally supported in any suitable manner to the frame of the machine in rear of the stapling nose, so that as said fork-shaped member is rocked on its pivot, the lasting 85 fingers depending from the branches thereof will be moved vertically. A spring C² connects the free end of the stem of the forked member C' with a portion of the frame of the machine positioned thereabove, such 90 spring serving to normally move the fork-shaped member to a position to cause the lasting fingers C C which depend from the brackets thereof to be projected below the lower end of the stapling nose B. In the 95 particular embodiment of the invention illustrated, the spring C² has its lower end connected to a bolt C⁴ which passes through the free end of the stem of the fork-shaped member C', and has threaded thereon a 100 suitable thumb nut, so that by adjusting the nut the tension of the spring C² may be varied. The fork-shaped member C' and the adjacent portion of the frame of the machine are provided with coöperating portions 105 for limiting the downward movement of the lasting fingers C C, and in the embodiment of the invention illustrated in the drawings, this is accomplished by providing the stem of the fork-shaped member with 110 an adjustable bolt C⁵, the upper end of which is adapted to contact with a portion of the frame of the machine, and thus constitute a stop to limit the movement of the 115 fork-shaped member on its pivot. Obviously, by adjusting the bolt C⁵, the extent to which the lasting fingers will project below the stapling nose, can be varied. While I have illustrated the yieldable lasting fingers as depending from the branches of the 120

fork shaped member C', it will be understood that various other constructions may be utilized and that if desired, each lasting finger may be independently supported and 5 independently adjustable to vary the amount which it may project below the stapling nose.

D designates a suitable standard or support which is positioned directly beneath the stapling nose B and in front of the main frame of the machine, the lower end of the support D being adapted to be connected either to the base of the machine or to the floor or 10 other support upon which the machine is positioned. Vertically movable within the standard or support D is a rod E, the upper end of which is adapted to carry a suitable anvil or work support to be hereinafter 15 more particularly set forth. The rod E and the work support carried thereby are adapted to be elevated by means of a suitable lever F, which is fulcrumed intermediate its ends to a support F', the lower end of which 20 is adapted to be connected either to the base of the machine or to the floor or other support to which the machine is secured, one end of said lever projecting through a slot d formed in the outer wall of the standard 25 or support D and into a slot e formed in the rod E. A chain F² depends from the outer end of the lever F, and the lower end of said frame will be conveniently connected to a suitable foot pedal or other operating member, not shown, supported by the base of the 30 machine, so that the workman may, by actuating said foot lever or operating member, exert a downward pull on the chain F² and thus actuate the lever F to elevate the rod E and the work support carried thereby. Secured to the inner end of the lever F is a 35 spring F³, the lower end of which is adapted to be connected to the base of the machine, said spring serving to normally hold the rod E and the work support carried thereby in its lowermost position.

The work support comprises a platform G which is secured to the upper end of the rod E and is adapted to overlie the top of the standard or support D and to extend rearwardly therefrom. The upper face of the platform G is provided with a dove-tailed way g therein in which is adapted to slide a dove-tailed projection h which extends from 50 the lower face of an anvil support H, which is adapted to rest upon the upper surface of the platform G and the rear end of which is provided with a downwardly turned portion h' in which is rotatably mounted an 55 adjusting screw h² which has a threaded engagement with the platform G. From this construction, it will be apparent that by manipulating the adjusting screw h² the anvil support H may be adjusted longitudinally 60 on the platform G. Pivoted secured

to the anvil support H by a pivot bolt l' which extends transversely of the anvil support is the anvil comprising the work supporting portion K and member I which is provided with an inclined face which is positioned directly beneath the stapling nose B of the machine, the anvil being pivotally supported so that the inclination of the face thereof may be varied. This is an important feature of the invention since it enables 70 the outer sole of the shoe which is to be stapled to be presented to the stapling nose at the proper angle to receive the staple. Where soles of considerable thickness are employed, the angle of the anvil need not be so pronounced, but where shoes having thin soles are to be made, it is necessary to support the sole at a substantial angle in order to prevent the staple, which is to be driven thereinto, from going entirely through the 75 sole. The work supporting portion K of the anvil is preferably adjustable, said work supporting portion being provided with a dove-tailed projection or key k projecting from the under surface thereof which slidably engages a dove-tailed key-way i which is formed in the face of the member I. Loosely mounted in the upper portion of the adjustable work supporting portion K is an adjusting screw k' which has a threaded engagement with the member I and is provided with a suitable thumb nut k² for adjusting the same. The work supporting portion K is provided with a flat outer surface k³ which extends at an acute angle to the horizontal platform G upon which the anvil support is slidably supported, the upper portion of which is beveled or inclined to form the surface k⁴ which extends at an angle to the surface k³. Extending rearwardly from one side of the member I of the anvil is an arm i' which is provided with a horizontally disposed slot i² in the end thereof.

L designates a rod which is provided at its upper end with a bifurcated portion l which embraces the end of the arm i' which extends from the member I of the anvil, and is pivotally connected thereto by means of a suitable bolt l' which passes through the arms of said bifurcated portion and the slot i² in the arm i'. As the pin l' loosely engages the slot in the arm i' extending from the anvil, it will be seen that this construction in no way interferes with the longitudinal adjustment of the anvil and its support upon the horizontal platform G. The rod L passes loosely through a horizontally disposed bracket M which is connected to the rod E so as to move therewith, and a suitable spring M' interposed between an abutment secured to the lower end of the rod L and the bracket M serves to hold the anvil in its normal position. Rigidly secured to the rod L above the bracket M is 130

a member N which is provided with an inclined upper surface n in which are formed a plurality of radially disposed grooves n' , and with a circumferentially disposed cam n^2 depending therefrom. 5 Loosely embracing the rod L and rotatably supported upon the upper surface of the bracket M is a lever O which is provided with an annular cam surface o projecting upwardly therefrom which is normally held in engagement with the cam surface n^2 of the member N by the coil spring M' heretofore referred to. Manifestly, by shifting the lever O the cam surface o thereof will 10 ride upon the annular cam surface n^2 of the member N and will effect the elevation of the rod L and consequently tilt the anvil upon its support. To hold the anvil in any desired position of adjustment, a detent lever 15 P is provided which is fulcrumed upon the lever O and is provided with an elongated end portion which is adapted to engage any one of the grooves n in the upper portion of the member N. The detent lever 20 O is normally held in engagement with one of the grooves n of the member N by means of a coil spring p which is interposed between the end of said detent lever and the lever O. 25 To facilitate the proper adjustment of the anvil for use in connection with soles of various thicknesses, the anvil support H and the platform G; the work supporting part K and the member I of the anvil; 30 and the member N and the detent lever P are preferably provided with coöperating scales enabling the parts to be instantly adjusted to the desired position by the workman for any desired thickness of sole. 35 In Fig. 3 of the drawing, there is illustrated in cross section on a last a shoe of the type, in the manufacture of which the present machine is intended to be used. The shoe comprises an outer sole Q having 40 a channel around the edge thereof, and an inner sole R which is secured to the outer sole, preferably by being cemented to the outer sole, and the outer edge of which overlies the channel in the outer sole; and 45 an upper A, the edge of which is adapted to be out-turned and secured in the channel of the outer sole, and it is desirable that the securing means for such upper pass into the shoulder formed at the inner side of 50 said channel. 55 In using the machine, the operator, after the outer sole and upper have been positioned on a last, holds the shoe with the outer sole thereof resting on the main inclined portion k^2 of the work supporting member K, with that portion of the outer sole which underlies the channel in the edge thereof overlying the upper beveled portion k^4 of the work supporting member. With 60 the shoe held in this position on the work 65 supporting face of the anvil a downward pull is exerted on the chain F² which causes the elevation of the anvil, and causes the lower ends of the lasting fingers to engage the edge of the upper and tuck the same between the edges of the inner and outer soles. As the upward movement of the anvil is continued the curved outer wiping surfaces $c c$ of the yieldable lasting fingers C C will be drawn across the upper and 70 will serve to smooth the upper properly over the lasting and properly position the edge thereof with reference to the outer sole. Upward movement of the anvil is continued until the work is brought firmly 75 into engagement with the lower end of the stapling nose B of the machine, and when the work has been brought to this position, the operator, by manipulating the usual handle or other operating member causes 80 a staple to be driven from the stapling nose through the upper and into the shoulder in the outer sole. It will be noted that by reason of the beveled upper surface k^4 of the work supporting face of the anvil K, 85 the outer edge of the sole will be forced downwardly at an angle with reference to the remainder of the sole when the sole is moved into engagement with the stapling nose, thus enabling the staple to be driven 90 into the shoulder portion of the channel. 95 As before stated it is desirable to vary the angle at which the outer sole will be supported during stapling according to the thickness of the sole, and when the anvil is 100 adjusted on its pivot, to vary the angle of the main surface k^3 of the work supporting face thereof it will be seen that the part k^4 of the work supporting face will be moved to an improper position with reference to 105 the stapling nose and hence the necessity of providing a work supporting face which can be adjusted longitudinally on the anvil and of providing an adjustment of the anvil itself upon the platform G. It will thus be 110 seen that regardless of the angular adjustment which is given to the anvil, the workman can always adjust the parts so that the two portions of the supporting face of the work supporting portions K of the anvil 115 will occupy their proper relative positions to the stapling nose. 120 While a convenient embodiment of the invention is illustrated in the accompanying drawings, it will be understood that many changes may be made in the particular form and construction therein shown without departing from the spirit and scope of the invention as defined in the appended claims. 125 I claim:— 130 1. A machine for lasting stitch-down shoes, having, in combination, fastening inserting means, comprising a fastening guide, and a lasting member yieldingly projected beyond the end of said guide along the line 135

- of insertion, whereby the upper is forced directly into the location in which it is to be secured by the fastening in advance of the engagement of the upper by the fastening 5 guide.
2. A machine for lasting stitch-down shoes having, in combination, fastening inserting means comprising a fastening guide reduced to an edge at its delivery end, and 10 a lasting member yieldingly projected beyond the end of said guide along the line of insertion, the end of said member being also reduced to an edge so located that when said member yields as the shoe to be lasted is 15 presented to said guide its edge will lie substantially in a line with the edge of said guide.
3. A machine for lasting stitch-down shoes having, in combination, fastening inserting means comprising a fastening guide tapered to an edge at its delivery end and lasting members located upon each side of said guide and having their ends reduced to edges arranged to form lateral upper engaging 20 extensions of the edge of said guide as the shoe to be lasted is presented to said guide.
4. A machine for lasting stitch-down shoes having, in combination, fastening inserting means comprising a fastening guide tapered to an edge at its delivery end and lasting members located upon each side of said guide, yieldingly projected beyond the 25 end of said guide and having their ends reduced to edges arranged to form lateral extensions of the edge of said guide as they are forced back by the presentation to said guide of a shoe to be lasted.
5. A machine for lasting stitch-down shoes having, in combination, fastening inserting means comprising a fastening guide reduced to an edge at its delivery end, a work support movable toward and away 30 from said guide along the line of insertion, and lasting members yieldingly projected beyond the end of said guide along the line of insertion, said members having their ends reduced to edges lying in a line substantially intersecting the line of insertion.
- 55 6. In a machine of the character described, a staple guiding member, a work support, a lasting member movably supported adjacent the staple guiding member, and normally projecting beyond the end thereof, and means for longitudinally shifting said staple guiding member and work support relatively to each other to effect an operation of said lasting member.
7. In a machine of the character described, 60 a staple guiding member, a work support, a yieldably supported lasting member positioned adjacent the staple guiding member and normally projecting beyond the end thereof, and means for longitudinally shifting said staple guiding member and said
- work support relatively to each other to effect an operation of said lasting member.
8. In a machine of the character described, a stapling nose provided with an opening therein and having a reduced lower end, a 70 work support positioned opposite the end of said stapling nose, a yieldably supported lasting finger positioned alongside of said stapling nose and extending along the line of insertion of the staple, said lasting finger 75 being provided with a reduced lower end, and means for shifting said stapling nose and work support relatively to each other along said line of insertion.
9. In a machine of the character described, 80 a stapling nose, a work support, a lasting finger positioned alongside of said stapling nose extending along the line of insertion of the staple, and having its front portion curved to provide a wiper surface, yieldable 85 means for normally positioning the lasting finger with the end thereof projecting beyond the end of the stapling nose, and means for shifting said stapling nose and work support relatively to each other along said 90 line of insertion.
10. In a machine of the character described, a stapling nose, a work support, a lasting finger positioned alongside of said 95 stapling nose, yieldable means for positioning said lasting finger with the end thereof beyond the end of the stapling nose, adjustable means for limiting the movement of said lasting finger, and means for shifting said stapling nose and work support relatively to each other.
11. In a machine of the character described, a stapling nose, a work support, a lasting finger positioned alongside of said 100 stapling nose, a spring tending to shift said lasting finger to project the end thereof beyond the end of the stapling nose, means for adjusting the tension of said spring, an adjustable stop for limiting the movement of said lasting finger by said spring, and means for shifting said stapling nose and work support relatively to each other.
12. In a machine of the character described, a stapling nose, a lasting finger positioned alongside of said 115 stapling nose and provided with a curved wiper surface, a spring tending to move said lasting finger to project the end thereof beyond the end of the stapling nose, a stop for limiting the movement of said lasting finger by said spring, and means for shifting said stapling nose and work support relatively to each other.
13. In a machine of the character described, a staple holding member, a work-support positioned opposite said staple holding member, a pair of movable lasting fingers positioned one on each side of said 120 staple holding member, the ends of said lasting fingers normally projecting beyond 130

the end of the staple holding member, and means for shifting the staple holding member and work support relatively to each other.

5 14. In a machine of the character described, a staple guiding member, a work support positioned opposite thereto, a pair of lasting fingers positioned one on each side of said staple guiding member, yieldable means for normally positioning the lasting fingers with the ends thereof projecting beyond the end of the staple guiding member, and means for longitudinally adjusting said work support and staple holding member 10 relatively to each other to effect an operation of said lasting fingers.

15. In a machine of the character described, a stapling nose, a work support positioned opposite thereto, a pair of yieldably supported lasting fingers positioned one at each side of said stapling nose, the ends of said lasting fingers normally projecting beyond the end of the stapling nose, and the front face of said lasting fingers being 20 curved to provide wiper surfaces, and means for adjusting said stapling nose and work support relatively to each other.

25 16. In a machine of the character described, a stapling nose, a pair of lasting fingers positioned one at each side of said stapling nose, yieldable means tending to move said lasting fingers to project the ends thereof beyond the end of the stapling nose, means for limiting the movement of said lasting fingers by said yielding means, a work support positioned opposite the stapling nose, and means for shifting said stapling nose and work support relatively to each other.

30 17. In a machine of the character described, a frame, a stapling nose fixedly supported by said frame, an adjustable work support positioned opposite said stapling nose, a lasting finger supported by the frame 45 and positioned alongside of said stapling nose, yieldable means tending to position said lasting finger with the end thereof projecting beyond the end of the stapling nose, and means for limiting the movement of 50 said lasting finger by said yieldable means.

55 18. In a machine of the character described, a frame, a stapling nose fixedly supported by said frame, a pair of lasting fingers movably mounted on said frame and positioned one on each side of said stapling nose, yieldable means for normally positioning the lasting fingers with the ends thereof projecting beyond the end of the 60 stapling nose, a work support positioned opposite the stapling nose, and means for adjusting said work support relatively to said stapling nose.

65 19. In a machine of the character described, a frame, a stapling nose fixedly supported thereby, a forked member pivotally

connected to the frame in rear of said stapling nose, the ends of the branches of said forked member being provided with downwardly turned lasting fingers positioned one on each side of the stapling nose, a spring 70 normally tending to shift said forked member to project the ends of the lasting fingers beyond the end of the stapling nose, a work support positioned opposite the stapling nose, and means for adjusting the work support 75 relatively to the stapling nose.

20 20. In a machine of the character described, a frame, a stapling nose fixedly supported thereby, a forked member pivotally connected to the frame in rear of said stapling nose, the ends of the branches of said forked member being provided with downwardly turned lasting fingers positioned one on each side of the stapling nose, a spring 80 normally tending to shift said forked member to project the ends of the lasting fingers beyond the end of the stapling nose, an adjustable stop for limiting the movement of said forked member by said spring, a work support positioned opposite the stapling 85 nose, and means for adjusting said work support relatively to the stapling nose.

21. In a machine of the character described, the combination with stapling mechanism of a work support positioned 95 therebelow, said stapling mechanism and work support being movable relatively to each other, said work support comprising an anvil having an inclined work supporting face provided with two surfaces arranged 100 at an angle to each other for engaging different portions of the sole.

22. In a machine of the character described, the combination with stapling mechanism, of a work support comprising a 105 pivoted anvil provided with an inclined face, a work supporting member slidably mounted upon the inclined face of said anvil, and means for adjusting the work supporting member on the face of the anvil. 110

23. In a machine of the character described, the combination with stapling mechanism, of a work support comprising a pivoted anvil provided with an inclined face, a work supporting member slidably 115 mounted upon the inclined face of said anvil, and means for adjusting the work supporting member on the face of the anvil, said work supporting member being provided with a flat surface, the upper portion 120 of which is beveled.

24. In a machine of the character described, the combination with stapling mechanism, of a work support, said work support comprising a vertically adjustable member, 125 an anvil support carried by said vertically adjustable member, means for adjusting the anvil support transversely of said vertically adjustable member, an anvil pivoted to said anvil support and provided with an inclined 130

work supporting face, and means for adjusting said anvil on its pivot.

25. In a machine of the character described, the combination with stapling mechanism, of a work support comprising a vertically adjustable member, an anvil support carried by said vertically adjustable member, means for adjusting said anvil support transversely of the vertically adjustable member, an anvil pivotally supported on said anvil support and provided with an inclined face, a work supporting member slidably secured to the inclined face of said anvil and adjustable longitudinally thereof, and means for adjusting the anvil on its pivot.

26. In a machine of the character described, the combination with stapling mechanism, of a work support comprising a vertically adjustable member, an anvil support carried by said vertically adjustable member, means for adjusting the anvil support transversely of the vertically adjustable member, an anvil pivotally connected to said anvil support and provided with an inclined face, a work supporting member slidably mounted on the inclined face of said anvil, said work supporting member being provided with a flat surface having a beveled upper portion, means for adjusting the work supporting member on the inclined face of the anvil, and means for adjusting the anvil on its pivot.

27. In a machine of the character described, a frame, a downwardly extending stapling nose fixedly supported by said frame, a pair of yieldably supported lasting fingers carried by the frame and positioned one on each side of said stapling nose, the lower ends of said lasting fingers normally projecting below the end of the stapling nose, and a vertically adjustable work support positioned below said stapling nose, said work support comprising an anvil having an inclined work supporting face, the upper portion of which is beveled.

28. In a machine of the character described, a frame, a downwardly extending stapling nose fixedly supported by said frame, a pair of yieldably supported lasting fingers carried by the frame and positioned one on each side of said stapling nose, the lower ends of said lasting fingers normally projecting below the end of the stapling nose, a vertically adjustable work support positioned below said stapling nose, said work support comprising an anvil having an inclined face, and a work supporting member adjustably mounted on the inclined face of said anvil, the upper portion of the outer surface of said work supporting member being beveled.

29. In a machine of the character described, a frame, a downwardly extending stapling nose fixedly supported by said

frame, a pair of yieldably supported lasting fingers carried by the frame and positioned one on each side of said stapling nose, the lower ends of said lasting fingers normally projecting below the end of the stapling nose, a vertically adjustable work support positioned below said stapling nose, said work support being provided with a pivoted anvil having an inclined face, and a work supporting member adjustably mounted on the inclined face of said anvil, the upper portion of the outer surface of said work supporting member being beveled.

30. In a machine of the character described, a frame, a fixed stapling nose carried by said frame, a pair of yieldably supported lasting fingers carried by the frame, the lower ends of said lasting fingers projecting below the lower end of the stapling nose, a work support positioned below said stapling nose, said work support comprising a vertically adjustable member provided with a horizontally disposed platform at the upper end thereof, an anvil support positioned on said horizontally disposed platform, and adjustable transversely thereof, an anvil pivotally mounted on said anvil support, and means for adjusting said anvil on its pivot, said anvil being provided with an inclined work supporting face, the upper portion of which is beveled.

31. In a machine of the character described, a frame, a fixed stapling nose carried by said frame, a pair of yieldably supported lasting fingers carried by the frame, the lower ends of said lasting fingers projecting below the lower end of the stapling nose, a work support positioned below said stapling nose, said work support comprising a vertically adjustable member provided with a horizontally disposed platform at the upper end thereof, an anvil support positioned on said horizontally disposed platform, and adjustable transversely thereof, an anvil pivotally mounted on said anvil support, means for adjusting said anvil on its pivot, said anvil being provided with an inclined face, and a work supporting member adjustably mounted on the inclined face of said anvil, the upper portion of the outer surface of said work supporting member being beveled.

32. In a device of the character described, the combination with a stapling mechanism, of a work support comprising a vertically adjustable member, an anvil pivotally mounted on said vertically adjustable member, and means for adjusting said anvil on its pivot comprising a bracket secured to the vertically adjustable member, a rod passing through said bracket and pivotally connected at its upper end to said anvil, a spring normally tending to shift said rod in one direction, and means for adjusting the rod in the other direction comprising a cam member

fixedly secured to the rod, and a lever loosely encircling said rod and provided with a cam member engaging the cam member fixedly secured to the rod.

33. In a device of the character described, the combination with a stapling mechanism, of a work support comprising a vertically adjustable member, an anvil pivotally mounted on said vertically adjustable member, and means for adjusting said anvil on its pivot comprising a bracket secured to the vertically adjustable member, a rod passing through said bracket and pivotally connected at its upper end to said anvil, a spring normally tending to shift said rod in one direction, and means for adjusting the rod in the other direction comprising a cam member fixedly secured to the rod, and a lever loosely encircling said rod and provided with a cam member engaging the cam member fixedly secured to the rod, and means for holding said lever in various positions of adjustment.

34. In a machine of the character described, a work support comprising a vertically adjustable member, an anvil pivotally mounted upon said vertically adjustable member, a bracket extending from said vertically adjustable member, a rod passing loosely through said bracket and having its upper end pivotally connected to said anvil, a spring normally tending to shift said rod in one direction, an annular member fixedly secured to said rod above the bracket, and provided with a plurality of notches in the upper portion thereof, and with a cam surface depending therefrom, a lever loosely encircling said rod and provided with a cam surface normally engaging the cam surface of the member secured to the rod, and a detent pivoted to said lever and provided with a portion adapted to engage with one of the notches in the member secured to said rod.

35. In a machine of the character described, a work support comprising a vertically movable member provided with a horizontal platform at the upper portion thereof, an anvil support slidably mounted on said platform, means for adjusting the anvil support on the platform, an anvil pivotally mounted on said anvil support and provided with an arm extending therefrom and having a slot in the outer end thereof, a bracket extending laterally from the vertically ad-

justable member in the work support, a rod 85 passing loosely through said bracket, a pin passing through the upper end of said rod, and the slot in the arm extending from the anvil, a spring tending to move said rod in one direction, and means for adjusting said 60 rod in the opposite direction.

36. In a machine of the character described, a work support comprising a vertically movable member provided with a horizontal platform at the upper portion thereof, 65 an anvil support slidably mounted on said platform, means for adjusting the anvil support on the platform, an anvil pivotally mounted on said anvil support and provided with an arm extending therefrom and 70 having a slot in the outer end thereof, a bracket projecting laterally from the vertically adjustable member in the work support, a rod passing loosely through said bracket, a pin passing through the upper 75 end of said rod and the slot in the arm extending from the anvil, a spring tending to move said rod in one direction, and means for adjusting said rod in the opposite direction, said means comprising coöperating 80 cam surfaces, one of said cam surfaces being fixedly secured to said rod and the other of said cam surfaces being carried by an adjusting lever loosely encircling said rod.

37. In a machine for lasting uppers to the soles of shoes, the combination with a support, of stapling instrumentalities, and means acting automatically in advance of the stapling operation and substantially in the plane of insertion of the staple for 90 pressing and stretching the edges of the upper at points adjacent to and on opposite sides of the stapling instrumentalities.

38. In a machine for lasting uppers to the soles of shoes, stapling instrumentalities, in 95 combination with a work support having two surfaces for supporting different portions of the sole, said surfaces being arranged at an angle to each other and meeting near the line of insertion, and means for 100 causing a relative movement between the work support and stapling instrumentalities.

In testimony whereof I affix my signature in presence of two witnesses.

ADAM H. PRENZEL.
